UNITED STATES PATENT OFFICE.

FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON SHOES.

1,069,977.

Specification of Letters Patent. Patented Aug. 12, 1913.

Application filed November 4, 1912. Serial No. 729,235.

To all whom it may concern:

Be it known that I, FREDERICK H. PERRY, a citizen of the United States, residing at Beverly, in the county of Essex and State of Massachusetts, have invented certain new and useful Improvements in Machines for Operating on Shoes; and I do hereby declare the following to be a full, clear, and exact description of the invention, such as will enable others skilled in the art to which it appertains to make and use the same.

The invention relates to machines for operating on shoes, and more particularly to mechanism for actuating the pattern cam or other pattern mechanism of machines in which the path of travel of the tool or devices operating on the shoe is determined by a pattern cam or mechanism.

The invention is designed primarily to improve the pattern cam actuating mechanism of the rounding and channeling machine shown and described in Patent No. 1,030,606, dated June 25, 1912, and is illustrated as embodied in that machine. The invention is not confined, however, in its application to this machine, but may be embodied in other forms of rounding and channeling machines, or in machines for performing other operations upon shoes.

The invention consists of the features of construction and combinations of parts hereinafter described and referred to in the claims, the advantages of which will be obvious to those skilled in the art.

The features of the invention will be readily understood from an inspection of the accompanying drawings, and the following detailed description of the construction illustrated therein.

In the drawings, Figure 1 is a side elevation of so much of the rounding and channeling machine of the above patent as is necessary to illustrate the application of the present invention thereto; Fig. 2 is a side elevation showing the pattern cam actuating and controlling mechanism; Fig. 3 is a detail sectional view on line 3—3, Fig. 2; Fig. 4 is a detail plan view showing the pawl controlling slides; Fig. 5 is a detail side elevation of the pawl controlling slides; Fig. 6 is a sectional view on line 6—6, Fig. 4; Figs. 7 and 8 are detail views showing the pawl controlling slides; and Fig. 9 is a detail of the slide operating block.

The machine illustrated is provided with 55 a trimming knife 1, a channel knife block 2 carried in the slide 3, a crease guide 4, a feeding jaw 5, and a forepart guide 6 which is carried by an arm 7. The arm extends forward from a yoke 8 which is pivotally 60 mounted in the frame of the machine and carries a laterally adjustable roll 9, as more fully described in the patent referred to. When the forepart guide is moved down into operative position by the operator in 65 passing from the shank on to the forepart, the relative position of the forepart guide and trimming knife is controlled to give the desired outline to the sole about the forepart by one of a series of cams 10 arranged 70 to be engaged by the roll 9. The pattern cams are carried by a shaft arranged in line with and connected to turn with the shaft 11. The cams are intermittently advanced during the operation of the machine, and each 75 cam is shaped to so vary the position of the forepart guide during the rounding operation as to give a predetermined contour to the forepart of the shoe sole. In order that the cams may be used in operating upon 80 both right and left shoes, the means for actuating the cams is so constructed that the movements of the cams may be reversed, the cams being driven in one direction while operating upon right shoes, and in the re- 85 verse direction while operating upon left shoes. In the construction shown the shaft 11 is actuated to advance the pattern cams through a ratchet wheel 12 secured to the lower end of a shaft 13 which is connected 90 with the shaft 11 through the worm 14, the worm wheel 15 and sleeve 16, as more fully shown and described in the patent above referred to. The ratchet wheel is operated by one or the other of two pawls 17 and 18 95 mounted in the arms of a bell crank lever 19 and arranged on opposite sides of the ratchet wheel. The pawls are forced in a direction to engage the ratchet wheel by springs 20 and 21, and are normally held 100 out of engagement with the wheel by guards 22 and 23 arranged to engage depending lugs 24 and 25 on the pawls. The pawl carrying lever 19 is connected by a link 26 with a lever 27 which is continuously oscillated by mechanism fully shown and described in the patent above referred to. When the pawl 17 is in engagement with the

ratchet wheel, the pattern cams are rotated in the proper direction for operating upon left shoes, and when the pawl 18 is in engagement with the ratchet wheel, the pattern cams are driven in the proper direction for operating upon right shoes.

The pawls are normally held out of engagement with the ratchet wheel by the guards, and one or the other of the guards is actuated by the operator, either in passing from the shank on to the forepart, or at the proper point during the operation upon the forepart of the shoe to start the feed or advance movement of the pattern cam. At the completion of the forward movement of the pattern cam, the active pawl is automatically disengaged from the ratchet, so that the mechanism is relieved from the wear to which it would otherwise be subjected. The automatic disengaging of the pawl at this time also enables the frictional connection between the ratchet wheel and pattern cams to be dispensed with if desired. The mechanism for operating and controlling the pawls comprises two slide plates 28 and 29 carrying the guards 22 and 23 respectively, and mounted side by side in a fixed guideway. The slide plates are connected by a spring 30 arranged in grooves formed in the adjacent faces of the slides, one end of the spring being connected to a pin 31 on the slide 28, and the other end to a pin 32 in the slide 29. The spring acts to hold both slides in normal position, with the rear end of the slide 29 in engagement with one side of a stop pin 33, and with a finger 34 on the slide 28 in engagement with the opposite side of the stop pin, thus holding the guards 22 and 23 in position to retain the pawls out of engagement with the ratchet wheel. The devices through which the operator actuates the slide plates 28 and 29 comprise a lever 35 provided with a pivot stud 36, the axis of which is arranged between two pins 37 and 38 which project laterally from the slides 28 and 29 respectively. The slide 29 is cut away at 39 for the passage of the pin 37. The lever 35 is provided with a vertical guideway in which a pivot block 40 is connected with a block 40 is mounted, so that it may be moved into position to engage either the pin 37 or the pin 38. The lever is also provided with a horizontal arm which is grooved to receive a pivot block 41 carried by a vertically sliding bar 42. The bar 42 is connected by a link 43 with devices through which the operator may draw down the bar, a spring 44 being provided to return the bar to normal position when the actuating devices are released by the operator, as fully shown and described in the patent above referred to. When the bar 42 is drawn downward by the operator, the lever 35 is rocked, and the block 40 will engage either the pin 37 or the pin 38, and

move either the slide 29 or the slide 28 in a direction to allow the pawl controlled by it to engage the ratchet wheel. If the block 40 is in the position indicated in the drawings, when the lever is rocked, the block will engage the pin 37 and draw the slide 28 toward the right, thus throwing the pawl 17 into operation, so that the pattern cams will be advanced in the proper direction for operating upon a left shoe. If the block 40 is in position below the pivotal axis of the lever 35, the block will engage the pin 38, and will move the slide 29 toward the left to throw the pawl 18 into operation, so that the pattern cams will be advanced in the proper direction for operating upon a right shoe. When the slide 28 is actuated to throw the pawl 17 into operation, it is held in position against the tension of the spring 30 by a latch 45 which is arranged to engage a notch 46 in the lower edge of the slide. The pawl 17 will therefore remain in action until the latch 45 is disengaged from the notch 46, so that the slide 28 may return to normal position whereupon the guard 22 disengages the pawl from the ratchet wheel. When the slide 29 is actuated to throw the pawl 18 into action, it is retained in position against the tension of the spring 30 by a latch 47 arranged to engage the side 48 of the recess 39, so that the pawl remains in action until the latch is disengaged and the slide returned to normal position by the spring. The slide 29 is provided with a notch 49 in its lower edge arranged to register with the latch 45 when the slide is in normal position, and the slide 28 is provided with a notch 50 in its upper edge arranged to register with the latch 47 when this slide is in its normal position. When the latch 45 engages the notch 46 of the slide 28 to hold it in such position that the pawl 17 remains in action, the latch also engages the notch 49 on the slide 29, and locks it in position to retain the pawl 18 out of action. The pawl 18 cannot therefore be thrown into action while the pawl 17 is in engagement with the ratchet wheel. In a similar manner the latch 47, by engagement with the notch 50, locks the slide 28 in position to retain the pawl 17 out of action when the latch is in engagement with the shoulder 48, and is holding the slide 29 in such position that the pawl 18 remains in action. The latches 45 and 47 are arranged one above the other, and in position to be engaged and actuated by a lug 51 projecting from the block 40. At the completion of the movement of the pattern cam by the pawl 17, for instance, the block 40 is automatically moved from the position indicated in the drawings to a position at the right of the pin 38 in Fig. 5, so that the next time the operator draws down the bar 42 the pawl 18 will be thrown into operation to 130

feed the pattern cam in the opposite direction. The movement of the block 40 into position to set the pawl controlling mechanism, so that the pattern cam will be moved in the opposite direction when the actuating mechanism is again thrown into operation, also engages the lug 51 with the latch 45, so that the latch is disengaged from the slide 28, allowing the spring 30 to return the slide to normal position, and thus disengage the pawl 17 from the ratchet wheel. In a similar manner the movement of the block 40 into position to engage the pin 37 at the completion of the movement of the pattern cam by the pawl 18, disengages the latch 47 from the slide 29, and thus causes the pawl 18 to be disengaged from the ratchet wheel.

The block 40 is shifted at the completion of the movement of the pattern cams in either direction by pins 52 and 53 arranged to engage a lever 54 which is connected to the link 55 on which the block 40 is formed, through the devices shown in Fig. 2, and fully described in the patent above referred to. The pins 52 and 53 are adjustably secured to a disk 56 which is in turn secured to the shaft 11, and turns with the pattern cam.

While it is preferred to employ the specific construction and arrangement of parts shown and described in embodying the invention in the machine of the patent above referred to, it is to be understood that this construction and arrangement is not essential so far as the broader features of the invention are concerned, and may be varied and modified as found desirable or best suited to the construction of machine in which the invention is to be embodied.

Having explained the nature and object of the invention, and specifically described one form of machine in which it may be embodied, what is claimed is:—

1. A machine for operating on shoes, having, in combination, a tool, a guide, mechanism for varying the relative position of the tool and guide during the relative travel of the tool about the shoe, means for actuating said mechanism in either direction including two pawls one only of which is active at a time, and means for determining the movement of said mechanism in either direction and simultaneously disengaging the active pawl.

2. A machine for operating on shoes, having, in combination, a tool, a pattern mechanism for determining the path along which the tool operates, pawl and ratchet mechanism for feeding the pattern mechanism in opposite directions, and means for determining the movement of the pattern mechanism in either direction and for simultaneously disengaging the pawl and ratchet.

3. A machine for operating on shoes, hav-

ing, in combination, a tool, pattern mechanism for determining the path along which the tool operates, actuating mechanism including pawls for feeding the pattern mechanism in opposite directions, guards for rendering the pawls inactive, a starting device under the control of the operator for operating the guards to render a pawl active, and means operating upon the completion of the movement of the pattern mechanism in either direction for operating the guard of the active pawl to render the pawl inactive.

4. A machine for operating on shoes, having, in combination, a tool, pattern mechanism for determining the path along which the tool operates, actuating mechanism including pawls for feeding the pattern mechanism in opposite directions, starting devices under the control of the operator for rendering a pawl active, and means operating upon the completion of the movement of the pattern mechanism in either direction to disengage the active pawl.

5. A machine for operating on shoes, having, in combination, a tool, a guide, pattern mechanism for relatively actuating the tool and guide to determine the path along which the tool operates, mechanism for actuating the pattern mechanism, and means operating upon the completion of the movement of the pattern mechanism in one direction to throw out the actuating mechanism and set it to move the pattern mechanism in the opposite direction when again thrown in.

6. A machine for operating on shoes, having, in combination, a tool, a guide, a cam for relatively actuating the tool and guide during the travel of the tool about the shoe, mechanism for actuating the cam, and means operating upon the completion of the movement of the cam in one direction to throw out the actuating mechanism and set it to feed the cam in the opposite direction.

7. A machine for operating on shoes, having, in combination, a tool, a guide, a pattern mechanism for relatively actuating the tool and guide to determine the path along which the tool operates, mechanism for actuating the pattern mechanism in opposite directions for right and left shoes, devices controlled by the operator for throwing the actuating mechanism into operation, and mechanism for alternately setting said devices for right and left shoes and for automatically throwing the actuating mechanism out of operation.

8. A machine for operating on shoes, having, in combination, a tool, a pattern cam for determining the path along which the tool operates, mechanism under starting control of the operator for actuating the cam in either direction, means operating at the end of the movement of the cam in one direction to set the actuating mechanism to feed the cam in the opposite direction when next

started, and means for disengaging the actuating mechanism at the end of the movement of the cam in either direction.

9. A machine for operating on shoes, having, in combination, a tool, a guide, a pattern mechanism for relatively actuating the tool and guide to determine the path along which the tool operates, actuating devices for feeding the pattern mechanism in opposite directions for right and left shoes, a starting device operated by the operator, devices moving with the pattern mechanism for shifting the starting device into position to start the feed of the pattern mechanism in one direction as the pattern mechanism completes its movement in the opposite direction, and means for automatically disengaging the actuating mechanism as the pattern mechanism completes its movement in either direction.

10. A machine for operating on shoes, having, in combination, a tool, a guide, pattern mechanism for relatively actuating the tool, and guide to determine the path along which the tool operates, actuating devices for feeding the pattern mechanism in opposite directions for right and left shoes, a starting device operated by the operator, and devices for automatically disengaging the actuating mechanism as the pattern mechanism completes its movement in either direction.

11. A machine for operating on shoes, having, in combination, a tool, a guide, a pattern mechanism for relatively actuating the tool and guide to determine the path along which the tool operates, actuating devices for feeding the pattern mechanism in opposite directions for right and left shoes, stops connected to move with the pattern mechanism for determining its movement in either direction and for throwing out the actuating devices.

12. A machine for operating on shoes, having, in combination, a tool, a guide, a pattern mechanism for relatively actuating

the tool and guide to determine the path along which the tool operates, actuating devices for feeding the pattern mechanism in opposite directions for right and left shoes, stops connected to move with the pattern mechanism for determining its movement in either direction and for throwing out the actuating devices, and starting devices shifted by the stops to reverse the direction of feed of the pattern mechanism.

13. A machine for operating on shoes, having, in combination, a tool, pattern mechanism for determining the path along which the tool operates, actuating mechanism including pawls for feeding the pattern mechanism in opposite directions for right and left shoes, guards for rendering the pawls inactive, a starting device under the control of the operator for operating the guards to render the pawls active, latches for engaging the guards, stops connected to move with the pattern mechanism, and means operated by the stops for disengaging the latches.

14. A machine for operating on shoes, having, in combination, a tool, pattern mechanism for determining the path along which the tool operates, actuating mechanism including pawls for feeding the pattern mechanism in opposite directions, guards for rendering the pawls inactive, a starting device under the control of the operator for operating the guards to render the pawls active, stops connected to move with the pattern mechanism for determining its movement in either direction, latches for retaining the guards in position, and means operated by the stops for shifting the starting device from the position to operate one guard into position to operate the other guard and for operating the latches.
